(57) **CLAIM**

The ornamental design for a tank retaining bracket, as shown.

DESCRIPTION

FIG. 1 is a front perspective view of a tank retaining bracket showing our new design;

FIG. 2 is a left side elevation view thereof;

FIG. 3 is a right side elevation view thereof;

FIG. 4 is a rear elevation view thereof;

FIG. 5 is a front elevation view thereof;

FIG. 6 is a top plan view thereof; and,

FIG. 7 is a bottom plan view thereof.

The broken lines in FIG. 1 depict environmental subject matter only and form no part of the claimed design.
